UNITED STATES PATENT OFFICE

171,691

PRINTING PRESS

Henry Dreyfuss, South Pasadena, Calif., and Robert H. Hose, Mountainside, N. J., assignors to Davidson Corporation, Chicago, Ill., a corporation of Illinois

Application March 6, 1953, Serial No. 23,934

Term of patent 14 years

(Cl. D64—11)

To all whom it may concern:

Be it known that we, Henry Dreyfuss and Robert H. Hose, have invented a new, original, and ornamental Design for a Printing Press, of which the following is a specification, reference being had to the accompanying drawing, forming a part hereof.

Fig. 1 is a perspective view showing the front and one side of the printing press.

Fig. 2 is a side elevation thereof.

Fig. 3 is a perspective view showing the back and the other side of the printing press.

We claim:

The ornamental design for a printing press, as shown.

HENRY DREYFUSS.
ROBERT H. HOSE.
